ENGINE STARTER CONTROL

Kenneth F. Douglas, Elmira, N. Y., assignor to
 Bendix Aviation Corporation, South Bend, Ind.,
 a corporation of Delaware

Application February 1, 1939, Serial No. 254,069

8 Claims. (Cl. 290—38)

The present invention relates to an engine starter control and more particularly to a two-stage starting system in which the starter gearing is engaged by partial energization of the starting motor, after which the motor is fully energized for cranking purposes.

It is an object of the present invention to provide a novel two-stage starting system incorporating a device for interposing a time delay between the initial actuation of the starting motor and the full energization thereof.

It is another object to provide such a device in which the initial energization of the motor is controlled by a starting switch and a resistor, and the full energization of the motor is controlled by a second switch which bridges the resistor.

It is another object to provide such a device in which the time delay is arranged to prevent closure of the second switch until a predetermined time after closure of the starting switch.

Another object is to provide such a device in which the time delay mechanism is actuated by the closure of the starting switch.

Further objects and advantages will be apparent from the following description taken in connection with the accompanying drawing in which:

Fig. 1 is a semi-diagrammatic illustration of a preferred embodiment of the invention; and

Fig. 2 is a similar illustration of a second embodiment thereof.

In Fig. 1 of the drawing there is illustrated a starting system comprising a battery 1 grounded at 2 and connected by leads 3 and 4 to a magnetic starting switch indicated generally by numeral 5 comprising fixed contacts 6 and 7 and a movable contact 8 mounted on a magnetic plunger 9. Contact 7 of the starting switch is connected by a lead 10 to a resistor R which in turn is connected by a lead 11 to a starting motor SM which is grounded at 12 to complete the starting circuit. It will be understood that the motor is arranged to actuate a starter gear of conventional type to engage and crank a member of the engine to be started, but since these elements are of the usual construction, it is deemed unnecessary to further illustrate them.

A control circuit for the magnetic starting switch 5 is provided comprising a manual switch 13 connected by a lead 14 to the battery lead 3 and by a lead 15 to a solenoid 16 which is arranged when energized to attract the plunger 9 to cause closure of the starting switch. Solenoid 16 is connected by a lead 17 to the starting motor

lead 11 whereby the control circuit is completed through the starting motor and the ground 12.

Means for providing a bridging circuit around the resistor R and starting switch 5 is provided comprising a lead 18 which connects the battery lead 3 to a magnetic bridging switch indicated generally by numeral 19. Switch 19 comprises a fixed contact 21 connected to lead 18 and a movable contact 22 mounted on an armature 23 pivoted at 24 and connected by a lead 25 to the starting motor.

A control circuit for the magnetic bridging switch 19 is provided comprising a contact 26 mounted on a spring 27 and arranged to be engaged by the movable contact 8 of the starting switch upon closure of the starting switch. Contact spring 27 is anchored at 28 and connected by a lead 29 to a flat spring member 31. Spring member 31 carries a movable contact 32 arranged to engage a fixed contact 33 which is connected by a lead 34 to an electromagnet 35 arranged when energized to attract the armature 23 of the bridging switch 19 to cause closure of said switch. Electromagnet 35 is connected by a lead 36 to a thermostatic conducting element 37 anchored at 38 and having at its free end a contact 39. Contact 39 is arranged normally to engage a fixed contact 41 which is connected by a lead 42 to a generator G driven by the engine to be started, whereby self-operation of the engine causes the generator to oppose the voltage of the battery 1 through the control circuit for the bridging switch 19, thus causing deenergization of the control circuit and opening of the bridging switch.

Contacts 32 and 33 of the control circuit for the bridging switch are normally closed, but means are provided for setting the contact 32 in vibration when the starting switch is closed to prevent effective energization of the control circuit for the bridging switch for a predetermined time. As here shown, this means comprises a weight member or bob 43 on the end of the flat spring 31 positioned adjacent an enlargement 44 on the end of the magnetic plunger 9 of the starting switch, the inclined sides of which enlargement are arranged to engage the weight 43 and set it in vibration when the starting switch closes.

Means for holding the bridging switch 19 closed irrespective of opening of the starting switch 5 is provided comprising a contact 45 mounted on the end of the armature 23 in position to engage a fixed contact 46 which is con-

nnected by a lead 47 to the lead 34 for the electromagnet 35.

Means for causing deenergization of the control circuit for bridging switch 19 after a predetermined time of cranking is provided comprising a heating coil 48 for the thermostatic element 31, which heating coil is connected by a lead 49 to the bridging switch member 23 and by a lead 51 to a ground connection 52.

10 In the operation of this embodiment of the invention, closure of the manual switch 13 completes the control circuit for the starting switch 5 from battery 1 through leads 3 and 14, switch 13, lead 15, solenoid 16, lead 17 and starting motor SM to the ground at 12. Solenoid 16 is thereby energized and attracts the plunger 9, causing closure of the starting switch 5. Closure of switch 5 completes the starting circuit from battery 1 through leads 3 and 4, contacts 6, 8 and 7, lead 10, resistor R, lead 11 and starting motor SM to the ground at 12. The starting motor is thereby energized from the battery with a voltage suitably reduced by the resistor R to cause engagement of the starting gearing 25 without damage thereto.

Closure of the starting switch also connects the contact 26 to the battery 1 by engagement with the movable contact 8 of the starting switch. At the instant of closure, however, contact 32 is 30 set in vibration by virtue of its mounting on the pendulous member 31, the bob 43 of which has been set in motion by the enlargement 44 on the end of the plunger 9. After a predetermined time of vibration, contact 32 comes to rest against contact 33 whereupon the control circuit for the bridging switch 19 is completed from the contact 26 through spring 27, lead 29, spring 31, contacts 32, 33, lead 34, electromagnet 35, lead 36, thermostat 37, contacts 38, 41, lead 42 and generator G which is grounded at 53. The consequent energization of the electromagnet 35 closes the bridging switch 19, thereby closing the bridging circuit around starting switch 5 and resistor R comprising lead 18, contacts 21, 22, 45 armature 23 and lead 25. Full battery voltage is thus applied to the starting motor to energize it for the cranking operation.

Closure of said bridging circuit causes deenergization of the solenoid 16 of the starting switch 50 whereby the starting switch opens. The bridging switch 19 is maintained closed, however, by the holding circuit comprising contacts 45, 46 and lead 47 so that cranking continues. When the engine starts, electromagnet 35 of the bridging switch is deenergized by the generator G which is connected to oppose the flow of current from the battery through said electromagnet, whereby the various elements of the starter control return to their original positions. If the engine 60 should fail to start after a predetermined time of cranking, thermostatic contacts 38, 41 will open, thus deenergizing the electromagnet 35 and interrupting the cranking operation.

In the embodiment of the invention illustrated 65 in Fig. 2, the starting circuit, the bridging circuit and the control circuit for the bridging switch are all similar to the corresponding features of the embodiment illustrated in Fig. 1 and are similarly numbered. In this embodiment 70 of the invention, however, closing means for the starting switch which operate the vibrator time delay and a separate holding means for the starting switch are provided.

As here shown, the closing means for the starting switch comprises a plunger 54 slidably

mounted within a solenoid 55 in position to engage the end of the plunger 9 of the starting switch and cause closure of the switch upon energization of solenoid 55. A control circuit for solenoid 55 is provided comprising a lead 56 connecting the battery lead 3 to a manual switch 57. Switch 57 is connected by lead 58 to solenoid 55, the opposite end of which solenoid is grounded at 59 to complete its control circuit.

Means for holding the starting switch 5 closed 10 is provided in the form of a solenoid 61 connected by a lead 62 to the starting circuit lead 18 and by a lead 63 to the starting circuit lead 11 on the opposite side of the resistor R.

Means are provided for setting in vibration the 15 pendulous contact carrying spring 31 of the control circuit for the bridging switch 19 in the form of a lever 64 pivoted at 65 and provided at its free end with a roller 66 arranged to engage the bob 43 of the vibrator. Lever 64 has fixed 20 thereon a laterally extending pin 67 positioned to engage a collar 68 fixed on plunger 54 whereby downward motion of plunger 54 swings the lever 64 down into engagement with the vibrator, causing contacts 32, 33 to be held open as long 25 as the plunger 54 remains in its lower position.

In the operation of this embodiment of the invention, closure of the manual switch 57 completes the control circuit for the solenoid 55 whereby plunger 54 is caused to move down and 30 engage the plunger 9 of the starting switch, thus closing the starting switch. The starting circuit through the resistor R is thus completed to energize the motor to cause engagement of the starter gearing as previously described. The 35 holding coil 61 of the starting switch is also energized by the voltage drop through the resistor R whereby the starting switch is held closed irrespective of deenergization of the closing means therefor.

Closure of the starting switch connects the contact 26 to the battery, but the control circuit for the bridging switch 19 is not completed since at this time contacts 32, 33 are held open by the action of the lever 64. When the operator opens 45 the manual switch 57, deenergizing the closing means for the starting switch, the parts thereof return to their idle positions and the lever 64 releases the vibrator time delay whereby after a predetermined period of vibration, contacts 32, 50 33 close, thus completing the control circuit for the bridging switch 19 and causing closure thereof. The full battery voltage is thus applied to the starting motor for cranking purposes. The holding coil 61 of the starting switch is deenergized by the closure of the bridging switch, but the bridging switch is held closed by virtue of the connection 47 from holding contacts 45, 46 which maintains the electromagnet 35 energized until the control circuit therefor is deenergized either 60 by the generator G responsive to self-operation of the engine or by the thermostat 37 after a predetermined time of cranking as herein above set forth.

Although but two forms of the invention have 65 been shown and described in detail, it will be understood that other embodiments are possible and various changes may be made in the design and arrangement of the parts without departing from the spirit of the invention as defined in the 70 claims appended hereto.

What is claimed is:

1. In an engine starter control, a starting circuit including a battery, a starting motor, a starting switch and a resistor, means including 75

a switch providing a bridge circuit around the resistor, and means whereby closure of the starting switch causes closure of the bridging switch, said closing means including a pair of contacts and means actuated by closure of the starting switch for vibrating said contacts a predetermined time before effective closure thereof.

2. In an engine starter control, a starting circuit including a battery, a starting motor, a starting switch and a resistor, means including a magnetic switch providing a bridge circuit around the resistor, and means whereby closure of the starting switch causes closure of the bridging switch, said closing means comprising a control circuit for the bridging switch including a fixed contact and a pendulously mounted contact, and means actuated by closure of the starting switch for closing the control circuit, said last means being arranged to set the pendulously mounted contact in vibration to delay effective closure of the control circuit for a predetermined time.

3. In an engine starter control, a starting circuit including a battery, a starting motor, a starting switch and a resistor for reducing the initial flow of current through said starting switch to the starting motor, means including a magnetic switch for short-circuiting the resistor, a control circuit for the magnetic switch including a pair of normally closed contacts, one of which is pendulously mounted, and manually controllable means for closing the starting switch and setting the pendulously mounted contact in vibration to delay effective closure of the control circuit for a predetermined time.

4. In an engine starter control, a starting circuit including a battery, a starting motor, a starting switch and a resistor for reducing the initial flow of current through said starting switch to the starting motor, means including a magnetic switch for short-circuiting the resistor, a control circuit for the magnetic switch including a pair of contacts closed by closure of the starting switch, a pair of normally closed contacts in series therewith, one of which is pendulously mounted, manually controllable means for closing the starting switch and setting the pendulously mounted contact in vibration to delay effective closure of the control circuit, and means responsive to self-operation of the engine to de-energize the control circuit.

5. In an engine starter control, a starting circuit including a battery, a starting motor, a starting switch and a resistor for reducing the initial flow of current through said starting switch to the starting motor, means including a magnetic switch for short-circuiting the resistor, a control circuit for the magnetic switch including a pair of contacts closed by closure of the starting switch, a pair of normally closed contacts in series therewith, one of which is pendulously mounted, manually controllable means for closing the starting switch and setting the pendulously mounted contact in vibration to delay effective closure of the control circuit, and means for deenergizing the control circuit after a predetermined time of cranking.

6. In an engine starter control, a starting circuit including a battery, a starting motor, a starting switch and a resistor for reducing the voltage of the battery, a magnetic switch for bridging said resistor, a control circuit for the magnetic switch comprising contacts closed by closure of the starting switch, and means responsive to self-operation of the engine to be started for deenergizing the control circuit.

7. In an engine starter control, a starting circuit including a battery, a starting motor, a starting switch and a resistor for reducing the voltage of the battery, a magnetic switch for bridging said resistor, a control circuit for the magnetic switch comprising contacts closed by closure of the starting switch, and means for deenergizing the control circuit responsive to overloading of the starting circuit.

8. In combination with an engine starter including a battery, a starting motor, and means responsive to energization of the starting motor for establishing a driving connection from the starting motor to a member of the engine to be started, a two-stage starter control therefor including a starting switch, closure of which energizes the starting motor sufficiently to establish said driving connection, a second switch, closure of which causes the full battery voltage to be applied to the starting motor, said starting switch comprising a movable member, and means including a time delay actuating device operated by said movable member for causing closure of the second switch a predetermined time after closure of the starting switch.

KENNETH F. DOUGLAS.
